UNITED STATES PATENT OFFICE.

WILLIAM EDENBORN, OF ST. LOUIS, MISSOURI.

BARBED FENCE-WIRE.

SPECIFICATION forming part of Letters Patent No. 313,929, dated March 17, 1885.

Application filed February 5, 1883. (Model.)

To all whom it may concern:

Be it known that I, WILLIAM EDENBORN, of the city of St. Louis, in the State of Missouri, have invented a certain new and useful Improvement in Barbed Fence-Wire, of which the following is a specification.

My invention relates to an improvement in barbed and twined or twisted fence-wire in which two longitudinal wires are employed. My improvement consists in wires twined or twisted one over the other, having a very thin, flat web of metal connecting their adjacent sides of about one-third or one-fourth the thickness of the barb, the latter being about two-thirds the thickness of one of the wires, this thin web being left in the process of manufacture to prevent longitudinal displacement of the twin wires in the process of twining or twisting, while the thin web does not interfere with the twining or twisting of one wire over the other within a very short distance, as usual. Perforations or holes in the web are provided for the barbs.

In order that my invention may be fully understood, I will proceed to describe it with reference to the accompanying drawings, in which—

Figure 1 is a plan view of twin main wires connected together on adjacent sides by a very thin, flat web merely of sufficient thickness to keep them from moving longitudinally in the process of twining or twisting one wire over the other. Figs. 2, 3, 4, 5, 6, 7, 8, 9, 10, 11, 12, 13, 14, 15, 16, and 17 show various forms of barbs applied to such twin wire; Figs. 2 and 3, 4 and 5, 6 and 7, 8 and 9, 10 and 11, 12 and 13, and 14 and 15 being respectively transverse sections and plan views, and 16 and 17 transverse sections, of portions of my improved twin wire, the transverse sections of the twin wire showing the barbs in elevation. I prefer the form of barb shown in Figs. 4 and 5.

No description of the various forms of barbs illustrated is given, as they are clearly shown in the drawings.

A A represent the main wires connected by a thin, flat web, C, which has perforations or holes B at suitable distances apart to receive barbs D, which may be of any desired shape or form, several being shown. The wires may be drawn to the proper size to

leave the very thin, flat web C, which may be done by drawing a No. 5 wire rod with one draft to No. 7½, then passing it through two successive pairs of rolls, the first pair of rolls 55 to flatten it to, say, No. 12½ × 6, and the second pair of rolls to divide it centrally, the second pair of rolls being adjusted to reduce the wire into two parts, leaving a thin web, C, between them. After thus reducing the 60 rod, which leaves a web, as shown, about one-third or one-fourth the thickness of a barb, which is about two-thirds the thickness of a main wire, the web perforated, and the barbs applied, the main wires are twined or twisted 65 together, as shown in Fig. 17. Barbed and twined or twisted fence-wire thus produced has all the advantages of two-strand cable, where the strands are not connected by a web, is cheaper, because wires of less diameter 70 can be used and of the same strength, and an article of better quality and appearance produced, for where two unattached wires are used they generally vary in size and temper, one being softer than the other, and in either of these 75 cases the wire which is softer or of less diameter winds around the other, which results in an ill-appearing product, and also in one inferior in quality, because the larger or harder wire being straight and the other wire winding 80 around it, as stated, they cannot expand and contract together in different temperatures, while with my construction a different article is produced, for if one wire happens to be thin or soft in places the other is correspondingly 85 thin or soft, and thus they must twine or twist uniformly throughout.

I am aware that wire grooved longitudinally, leaving a web of sufficient thickness to be nicked up to form barbs, is old, that such 90 web has been slotted to receive barbs, and that such wire has been slightly twisted. Such construction, therefore, I do not claim, broadly, as in no instance that I am aware of have two complete main wires been formed with a very 95 thin, flat connecting-web while permitting the wires to be twined, twisted, or rolled side-wise one over the other, as usual.

I should state that the drawings represent my wire on a very large scale, to clearly indicate the details of construction.

I claim—

The herein-described improved twin fencing-wire, consisting of two main wires connected by a very thin, flat web, said web being perforated, as described, and provided with 5 wire barbs secured in the perforations, and the twin wires being twisted, twined, or rolled sidewise one over the other, whereby the per-

forations of the web are closed around the barbs and the latter caused to project at different angles, as shown and described.

WILLIAM EDENBORN.

In presence of—
SAML. KNIGHT,
GEO. H. KNIGHT.
